HAIR PARTING DEVICE

Filed Nov. 28, 1950

INVENTOR.
ERWIN HELFGOTT
BY *Leon M. Szwarc*
ACT.

According to the present invention, the hair parting device is the result of a combination of several factors. The first is the use of a flexible, resilient, and relatively soft material, such as a synthetic rubber, which is capable of being easily bent and twisted without breaking. The second factor is the use of a series of sharp, pointed, and slightly curved teeth or prongs, which are arranged in a series of rows, and which are designed to grip the hair firmly and yet not damage it. The third factor is the use of a handle or gripping means, which is attached to the device and which is used to hold the device in place during use.

UNITED STATES PATENT OFFICE

2,604,101

HAIR PARTING DEVICE

Erwin Helfgott, New York, N. Y., assignor to
Royal P. C. D. Inc., New York, N. Y., a corpo-
ration of New York

Application November 28, 1950, Serial No. 197,860

2 Claims. (Cl. 132—11)

This invention relates to a hair parting device or applicator, for home use as well as for professional use in beauty parlors and the like.

It is one of the objects of the invention, to facilitate the manufacture of a simple and inexpensive device which may be made from plastic material or plastic composition, or suitable metals which are resistant to the attack from dyes and other solutions used for the production of permanent waves for hair.

It is another object of the present invention to provide a hair parting device of the aforesaid character which may be easily conformed to the shape of the head of a person and may be applied to any part of the head (back, top or sides thereof) to facilitate obtainment of substantially equal hair strands to be worked upon.

Yet a further object of the present invention is to provide means ensuring the retainment of the hair parting device in its position on the head of a person whose hair is to be treated so that the operator will have the hands free for curling the hair or any other treatment.

Another object of the invention is the provision of means enabling the treated hair to be received in the arcuate-shaped surface of the teeth or prongs of the parting device which tooth surface contributes to easy insertion and retainment of a pin or curler into a set curl and easy retainment of said curl on top of the tooth.

Still another object of the present invention is to provide means ensuring sufficient flexibility of the teeth of the parting device and, at the same time, reinforcement of the relatively thin-walled teeth.

A still further object of the present invention is to provide means permitting the construction of the parting device with teeth of varying or adjustable length, sizes or colors to thereby adapt the device to the individual color of the hair to be treated.

Yet a further object of the invention is to provide means affording ready and easy application to and guidance of the device through the hair during insertion of the device.

Still another object of the present invention is to provide means facilitating an abutment against the forehead of a person's head for limiting the movement and preventing canting of the device from its required position during manipulation of the hair, and the employment of said abutment as a handle or gripping means for withdrawal of the device from the head without substantially disturbing the treated hair.

With the above and other objects in view, the

invention is comprised of the combination of the parts and parts of parts as hereinafter set forth, it being understood that all parts not specifically mentioned are of conventional construction and are not material to the present invention.

The invention is embodied in a hair parting device, which includes a body having a front rim, a middle finger or gripping piece, and a plurality of spaced apart relatively wide teeth or prongs, the upper surfaces of which are arcuately shaped, and which is designed to be applied to the hair of a person.

The invention is embodied in a hair parting device, which includes a body having a front rim, a middle finger or gripping piece, and a plurality of spaced apart relatively wide teeth or prongs, the upper surfaces of which are arcuately shaped, and which is designed to be applied to the hair of a person.

The invention is embodied in a hair parting device, which includes a body having a front rim, a middle finger or gripping piece, and a plurality of spaced apart relatively wide teeth or prongs, the upper surfaces of which are arcuately shaped, and which is designed to be applied to the hair of a person.

The invention will be hereinafter more fully described and the combination and arrangement of parts will be shown in the accompanying drawing and pointed out in the claims which form part of the specification.

In the drawing:

Fig. 1 is a top plan view of the hair parting device embodying the invention.

Fig. 2 is a front end view of the device of Fig. 1 with time means applied thereto.

Fig. 3 is an enlarged sectional view taken along line 3—3 of Fig. 1.

Fig. 4 is a sectional view taken along line 4—4 of Fig. 1.

Fig. 5 shows in perspective and in a diagrammatic manner the use of the parting device of Fig. 1 and applied to the hair of a person.

Referring now more specifically to the attached drawing, there is disclosed in Figs. 1 and 5 a parting device 10 having a body 11 with a forwardly and downwardly extending front rim 12. Rim 12 is provided with a middle finger or gripping piece 13 to facilitate insertion of the device 10 into and withdrawal of the latter from the hair 14 and to center said device therein. Rearwardly of body 11 extends a plurality of spaced apart relatively wide teeth or prongs 15 the upper surfaces of which are arcuately shaped, as best seen in Fig. 3.

Thus, each tooth includes a downwardly extending recess or trough defined by a curved surface 15a sufficient to provide enough stiffness and reinforcement for the otherwise relatively thin-walled flexible and resilient tooth. Each tooth 15 tapers into a free end piece 16 which terminates in a pointed end 17 which extends angularly to or is bent out of the plane of the remainder of each tooth.

These pointed tooth ends 17 form guide means during insertion of the device into the hair of a person's head and simultaneously space the teeth from the scalp a predetermined distance, so that the teeth extend between the head surface proper and the surface of the hair to be parted.

The teeth 15 has sufficient width and length to facilitate division of the hair in substantially equal number of bunches of hair strands for the ensuing hair treatment (permanent waving process, dyeing, curling, etc.).

It is further contemplated according to the invention to use different sizes of parting devices with predetermined or adjustable tooth lengths in accordance with the desired location on the head to be treated, and to employ colored or tinted material for the manufacture of the part-

ing device to conform the same to various hair shades or colors.

As will be apparent from Fig. 2 the rim 11 is somewhat curved in crosswise direction and the teeth 15 are disposed to extend in half-moon shaped fashion from said rim in order to readily conform the device to the shape of the head surface of a person.

If the body of the device is made of a plastic substance or plastic composition the device can be flexed or otherwise shaped to adapt same to the respective individual head surface (front, rear, sides thereof) to which the device is to be applied.

The lateral ends 18, 19 of body 10 are provided with perforations 18a, 19a to facilitate attachment of tie means 20 thereto, which may be in the form of a rubber band.

This tie means, as may be visualized from Fig. 5 contributes to a relatively firm hold of the device 10 when engaged in the hair 14 to be parted and subsequently treated. Thus, several tufts of hair 21, 22, 23 extend between adjacent teeth (other tufts being omitted in Fig. 5 for the sake of clarity), each tuft having approximately the same number of hair strands.

The hair tufts are easily guided between adjacent rounded side edges of neighboring teeth for position on and deviation to the surface of the teeth. The teeth 15 are also rounded at 15b where they join the rim body 11 so that the hair tufts are smoothly lodged between said tooth joints.

When, as illustrated in Fig. 5, these tufts of hair are individually set to curls 25 by means of curlers or pins, such as seen at 24, the curls may be placed for shape and support in the recessed or round surface 15a of the teeth 15 (Fig. 3) and are thus spaced from the head surface, which in turn is protected from direct influence of hair treatment lotions or fluids usually applied to curls, etc.

In order to anchor device 10 more firmly in place on the head of a person one of the teeth may include an extension piece or may be made of greater length than the other teeth and so shaped at its free end that tie means 20 may also be engaged by this extension end which is positioned in the hair remote from the other pointed ends 17 of the teeth.

It is well understood that after application of the parting device to the hair of a person the operator or person herself will have both hands free for treating the parted hair tufts.

It can thus be seen that there has been provided according to the invention a device for parting hair, which is characterized by a body provided with an abutment rim, and a plurality of spaced apart teeth adapted for the insertion into a person's hair and joined to and projecting a predetermined distance from said rim, each tooth terminating in a depending and pointed end for guiding said teeth during insertion thereof along the scalp of the person's head, each tooth being arcuate-shaped in cross-section to thereby reinforce the tooth and to form a recess in the upper surface thereof, in which hair tufts

extending between adjacent teeth may be placed in rolled condition.

While a preferred embodiment of the invention has been shown and herein described, it will be understood that the same is capable of modifications without departure from the general scope and spirit of the invention as defined in the claims:

Having thus described the invention, what is claimed as new and desired to be secured by Letters Patent, is:

1. A hair parting device comprising a concavely shaped transverse body adapted to conform to the scalp of a person and including an abutment rim extending below the top surface of said body and for position in contact with a person's forehead, and a plurality of spaced apart teeth for insertion into a person's hair, said teeth being joined to said body and extending in crosswise direction to and a predetermined distance from said rim, each of said teeth terminating in a pointed end extending below the top surface of said tooth and engageable with the person's scalp for guiding said teeth during insertion thereof and to space said teeth from the scalp, each tooth including an arcuately shaped recess portion extending longitudinally of the top surface of each tooth.

2. A hair parting device comprising a concavely shaped transverse body adapted to conform to the scalp of a person and including an abutment rim arranged centrally of said body and extending below the top surface thereof and for position in contact with the person's forehead, a plurality of spaced apart teeth for insertion in a person's hair, said teeth extending from said body in crosswise direction thereto and a predetermined distance from said rim, each of said teeth terminating in a pointed end depending below the top surface of each tooth and engageable with the person's scalp for guiding said teeth during insertion thereof, each tooth including an arcuately shaped recess portion extending longitudinally on the top surface of each tooth, and tie means fixed to and extending laterally from opposite ends of said transverse body and facilitating holding said teeth in place within the hair and securing of said body between said abutment rim and said pointed ends of said teeth.
